US00D927452S

(12) **United States Design Patent** (10) **Patent No.:** **US D927,452 S**
(45) **Date of Patent:** **** Aug. 10, 2021**

(54) **COMMUNICATIONS HEADSET OR HEADPHONE**

(71) Applicant: **Plantronics, Inc.**, Santa Cruz, CA (US)

(72) Inventors: **Nicholas W. Paterson**, Aptos, CA (US); **John A. Kelley**, Santa Cruz, CA (US)

(73) Assignee: **Plantronics, Inc.**, Santa Cruz, CA (US)

(**) Term: **15 Years**

(21) Appl. No.: **29/735,701**

(22) Filed: **May 22, 2020**

Related U.S. Application Data

(62) Division of application No. 29/663,896, filed on Sep. 19, 2018, now Pat. No. Des. 885,364.

CLAIM

The ornamental design for a communications headset or headphone, as shown and described.

DESCRIPTION

FIG. 1 is a front-left perspective view of a communications headset or headphone showing my new design;

FIG. 2 is a back-right perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines showing the unclaimed features form no part of the claimed design.

The broken lines immediately adjacent the shaded areas represent the bounds of the claimed design while all other broken lines are directed to environment that is for purposes of illustration only; the broken lines form no part of the claimed design.

1 Claim, 8 Drawing Sheets
